UNITED STATES PATENT OFFICE.

HARRY JAMES PRESTON, OF SAN JOSE, CALIFORNIA.

DETACHABLE-RIM FASTENER.

1,331,375.

Specification of Letters Patent. Patented Feb. 17, 1920.

Application filed July 6, 1918. Serial No. 243,534.

To all whom it may concern:

Be it known that I, HARRY J. PRESTON, a citizen of the United States, and a resident of San Jose, in the county of Santa Clara 5 and State of California, have invented a new and Improved Detachable-Rim Fastener, of which the following is a description.

My invention relates to means for fastening a detachable rim or the like on a wheel, and more particularly relates to the fastening lugs. In using the ordinary fastening lugs disposed about a wheel, the respective lugs are not always uniformly forced home 10 by the bolts or screws employed for fastening the lugs to the wheel felly, the result being that the detachable rim and the tire carried thereby are not accurately centered so as to be truly concentric with the axis of 15 the wheel, and moreover the rim as secured by the means usually employed for the purpose is not always positively restrained against creeping.

An important object of my invention is to 20 provide a fastening means involving a novel lug and appurtenances thereto, the use of which will accurately center the rim and positively prevent creeping. The stated object is attained by providing a lug which in 25 addition to its primary fastening function is provided with a secondary fastening means to secure the detachable rim at a point distant from the lug, thereby providing in connection with each lug two points of engagement with the rim, and in a manner to positively lock the rim against movement.

A further object of the invention is to 30 provide a secondary fastening means of such a character that it serves for facilitating the proper positioning of the lug.

Reference is to be had to the accompanying drawings forming a part of this specification, it being understood that the drawings are merely illustrative of one example 35 of the invention.

Figure 1 is a side elevation of a portion of a wheel and a detachable rim, together with my improved fastening means for the rim;

Fig. 2 is a plan or face view of the parts 40 shown in Fig. 1, a portion of the detachable rim being broken away;

Fig. 3 is a transverse section on the line 3—3, Fig. 1.

In the illustrated example, A indicates a 45 portion of a felly of a wheel, and B, the permanent rim or felly band thereon and it is

to be understood that the invention is applicable to any approved wheel. In carrying out my invention a lug 10 is provided to be placed against a side of the felly A to 60 which it is secured by a transverse bolt 11 or the like. Said lug as usual has a curved lip or flange 12 to lie against the adjacent side of the detachable rim 13 to be fastened, and has an elongated transverse tongue 14 65 at the side generally of tapering form, adapted to wedge between the permanent rim B and the rim 13. In order to provide an interlock the tongue 14 is formed with an end slot 15, thereby giving said tongue a 70 forked formation to accommodate and pass each side of a pin 16 extending radially inward at the inner side of the rim 13. Thus, when the tongue 14 is forced into position between the rim 13 and fixed rim B, the pin 75 16 entering the slot 15 effects a positive interlock between said fixed rim and the rim 13 to prevent creeping of the latter. In connection with the lug 10 I provide an auxiliary means to engage the rim 13 at a point 80

distant from the lug for which purpose a rod 17 is secured at one end to said lug by being received in a hole formed in the lug for the purpose as best seen in Fig. 3 and adjacent to the lug the said rod is bent laterally as at 18 whereby the rod for its major portion is offset laterally inward to extend along the approximate center of the felly A. The free end of the rod 17 terminates in a pin 19 extending radially outward whereby it 90 may be passed through aligned holes in the felly A, fixed rim B, and rim 13. Thus, the pin 19 affords a second fastening means for the rim 13 distant from the fastening effected by the lug 10. In practice, the pin 19 is 95 first passed through the felly and fixed rim B into engagement with the rim 13. The lug 10 in engagement with the end of the rod 17 therein is forced laterally inward into position so that the fastening of the lug by 100 the bolt 11 secures the auxiliary fastening pin 19 against displacement as well as securing the lug itself. The offset portion of the rod 17 lying at the interior of the felly A limits the movement of the pin 19 radially 105 outward.

By the use of the lug and the rod 17 with the pin 19 a materially reduced number of lugs will suffice to secure the rim, it having been found in practice that three lugs with 110 the described auxiliary fastening means will suffice to secure the largest rim employed.

By the positive interlocking of the rim 13 and lug by reason of the slot and pin 15, 16, together with the pin 19 the creeping of the rim is positively prevented. Also, the concentric position of the rim 13 is insured and the lateral position of the rim and the tire carried thereby are also insured since the pins 16, 19 are located at the median line of the rim.

10 It is to be understood that in practice the lug bolt or screw 11 has the usual flange for engaging the removable rim at the inside of the wheel or at the side opposite the member 12, the bolt 11 being only conventionally shown in the present instance since the lug at the inside is well known and forms no part of the present invention. In practice, it is to be understood also that the rod 17 has sufficient strength to serve its purpose and not be yieldable laterally to a degree to defeat the purpose of the invention. Also, the distance of the pin 19 from the lug 16 can be such as a manufacturer deems desirable for the particular wheel to which the invention is applied.

15 I would state in conclusion that while the illustrated example constitutes a practical embodiment of my invention, I do not limit myself strictly to the mechanical details herein illustrated, since manifestly the same can be considerably varied without depa-

ture from the spirit of the invention as defined in the appended claims.

Having thus described my invention, I claim as new, and desire to secure by Letters Patent:

1. The combination with a wheel and a detachable rim thereon having pins projecting radially inward from the inner side thereof, said rim furthermore having radial 40 pin holes distant from said pins, lugs having tongues adapted to be entered beneath the rim between the same and the wheel, said tongues having slots in the inner ends thereof adapted to accommodate said pins, a 45 member held at one end to each of said lugs and extending from the latter beneath the wheel felly, said members having pins thereon distant from the lugs and extending radially outward through the felly and into the 50 holes in said rim, and means to secure said lugs to the felly.

2. In a fastener for detachable rims, having a radial pin hole, a lug having a tongue adapted to enter beneath the rim, a rod received at one end in said lug and offset laterally to lie at the inner side of a wheel rim, and a pin on said rod distant from the lug projecting radially outward to be passed through the wheel felly and into the pin 60 hole of the rim.

HARRY JAMES PRESTON.
